UNITED STATES PATENT OFFICE

JACOB JENNE, OF CLEVELAND, OHIO, ASSIGNOR TO THE CLEVELAND PLANER COMPANY, OF CLEVELAND, OHIO, A CORPORATION OF OHIO

CONTROL MECHANISM FOR OPEN-SIDE PLANERS

Application filed June 11, 1928. Serial No. 284,436.

This invention relates generally to open side planers and are particularly to the combination of a rapid power traverse with the feeding mechanism on all of the heads of the machine which is so arranged and constructed that it will be impossible to engage the dial feeds and the power rapid traverse at the same time; and in which all of the heads can be operated by the rapid power traverse simultaneously, if desired.

The main object of the invention is to provide an open side planer of the character described which is comparatively simple and yet very efficient in operation and which will occupy a minimum space and at the same time turn out very accurate work.

Another object of the invention is to provide an open side planer which will reduce the operating cost and increase the speed and accuracy of the cut, and in which unnecessary motions of the operator are eliminated by placing all of the several controls and operating levers in such a position as to be within easy reach from the operator's seat at one side of the machine.

Another object of the invention is to provide a drive for the rapid power traverse which is adjustable with respect to the load in such a manner as to render the machine comparatively safe and which will prolong the life of the planer.

Another object of the invention is to provide an adjustable dial feed mechanism for moving the tool slides in any direction varying the feed from zero to one and one-quarter inches per stroke of the table and in which the starting point of the feed can be varied at either end of the table.

A still further object of the invention is to provide mechanism for operating the dial feed and rapid power traverse which is so arranged as to be controlled from the same side of the machine and in which it will be impossible to throw in the power traverse while the dial feed is operating or vice versa.

Further and more limited objects of the invention will appear as the description proceeds and by reference to the accompanying drawing illustrating the preferred embodiment of my invention and in which Fig. 1 is

a view in end elevation of an open side planer and illustrating the relative position of the mechanism to be hereinafter described; Fig. 2 is a fragmentary detail view in front elevation of the mechanism for moving the rail heads; Figs. 3 and 4 are vertical sectional views on the lines 3—3 and 4—4 respectively of Fig. 2; Fig. 5 is a detail view partly in front elevation and partly in vertical section of the drive for the rail and side heads and illustrating the improved form of clutch; Fig. 6 is a detail fragmentary view with parts broken away to illustrate the clutch members for the rapid power traverse and dial feed; Fig. 7 is a vertical sectional view disclosing the mechanism for operating the dial feed; Fig. 8 is a horizontal sectional view on the line 8—8 of Fig. 7; Fig. 9 is a vertical sectional view on the line 9—9 of Fig. 7; Fig. 10 is a fragmentary detail view showing the driving connection between the rail head and the threaded driving shaft and Fig. 11 is a similar fragmentary view showing the driving connection between the rail head and its driving shaft.

Referring now to the drawings, the reference character 1 designates the base or bed of the planer on which is mounted a table 2 which is adapted for reciprocatory movement thereon in a horizontal plane. Rising from the bed 1 is a column 3 on the front face of which is mounted the knee 4 which is adjustable thereon in a vertical plane. The knee 4 is raised and lowered by a shaft driven in any suitable manner well known to those skilled in the art. Secured to the knee 4 is a rail 6 on which are mounted rail heads 7 and 8 carrying tool slides 9 and 10 respectively. The rail 6 is substantially rectangular in shape and extending longitudinally thereof are shafts 11, 12 and 13 disposed one above the other. Also extending longitudinally of the rail and to the rear of shafts 11, 12 and 13 are shafts 14 and 15, the purpose of which will hereinafter appear. Also carried by the column 3 is the side head 16 provided with the usual tool slide 17. The side head is raised and lowered by means of a screw 18 in a manner to be described hereinafter. The table is reciprocated by suitable mechanism

which forms no part of this invention and hence will not be described in detail.

Mounted on the end of the rail 6 is a casing 19 in which is housed the control mechanism for the rail heads 7 and 8 and the side head 16. Carried by a bracket on the top of the planer is the power shaft 20 having suitable bearings and provided at one end with a cone faced driving disk 21 as shown most clearly in Fig. 5. Extending over and substantially enclosing the end of the driving disk 21 is a housing 22 in which is journaled a shaft 23 on the upper end of which is non-rotatably mounted a double faced disk 24, the opposite ends of which are frusto-conical in shape as shown most clearly in Fig. 5. Rotatably mounted on the upper end of the shaft 23 and slidable thereon is a clutch 25. This clutch serves to move the disk 24 either up or down to change the direction of rotation of the shaft 23. Journaled in the housing 22 is a horizontally disposed shaft 26 on which is non-rotatably secured a clutch shifting crank 27 the outer end of which engages in a groove in the clutch 25. The shaft 26 extends through the housing and rigidly secured to the outer end thereof is a gear segment 28. Disposed adjacent the gear segment 28 is a downwardly extending shaft 29 to the upper end of which is secured a gear 30 which meshes with gear segment 28. Secured adjacent the lower end of shaft 29 is a lever 31 by means of which the shaft may be turned. From an inspection of Figs. 2 and 5, it will be seen that the shaft 29 may be turned by the lever 31 to move the double faced disk 24 either up or down for the purpose of changing the direction of rotation of the shaft 23. The driving surfaces 32 and 33 of the disk 24 are frusto conical and have a covering of strawboard. The cone face of the disk 21 preferably has a covering of paper. It will thus be seen that I have provided a self contained reversible friction drive which will adapt itself to the load carried thus eliminating danger of breakage due to the driven parts becoming overloaded.

The driving mechanism for the rapid power traverse, that is, the mechanism for rapidly moving the rail heads and side head as distinguished from the dial feed will now be described. From an inspection of Figs. 2 and 5, it will be seen that the shafts 11, 12, 13, 14 and 15 project beyond the rail 6 and through the housing 19. As is clearly shown in Figs. 10 and 11 the driving connections between the threaded shafts 11 and 13 and the rail heads 7 and 8 are conventional, consisting merely of projections 7^a and 8^a on the rail heads 7 and 8 respectively and being threaded to receive the shafts 11 and 13, respectively. The shaft 23 projects through the housing 19 and has a suitable bearing at its lower end. Keyed on the shaft 23 and within the housing 19 is a worm 34 which meshes with and drives

a worm gear 35. By reference to Fig. 7, it will be seen that the shaft 15 has a sleeve 36 loosely mounted thereon. Keyed on the sleeve 36 is a bushing 37 on which a gear 35 is rotatably mounted. Also rotatably mounted on the bushing 37 and rigidly connected with the gear 35 is a spur gear 38 which meshes with a double faced gear 39 rotatably mounted on shaft 14. Keyed on shaft 14 immediately adjacent gear 39 is a double faced clutch member 40 adapted to be moved to clutch the gear 39 to shaft 14. A lever 41 serves as a means for moving the clutch member 40. Rotatably mounted on shafts 11, 12 and 13 are double faced gears 42, 43 and 44 respectively which mesh with each other as shown in Figs 3 and 6. These gears lie in the same plane as gear 38 and gear 38 meshes with and drives gear 43. Rotatably mounted on shafts 11, 12 and 13 are double faced intermeshing gears 42^a, 43^a and 44^a respectively. Slidably mounted on shafts 11, 12 and 13 are clutch members 45, 46 and 47 respectively, which are keyed to the shafts by keys 45^a, 46^a and 47^a. Control levers 48, 49 and 50 serve as a means for moving the clutch members to the right or left as seen in Fig. 6. It will thus be seen that when the control levers 41, 48, 49 and 50 are moved to the left as seen in Fig. 2, a driving connection will be provided between the power shaft 20 and the shafts 11, 12, 13 and 14 and that the direction of rotation of these shafts may be reversed by shifting the lever 31 which changes the direction of rotation of the shaft 23. The shaft 11 moves the far rail head 7 to the right or left in a horizontal plane. The shaft 13 moves the near rail head to the right or left in a horizontal plane. The shaft 14 is provided at its opposite end with a bevel gear 51 which meshes with a bevel gear 52 keyed on the threaded shaft 18. It will therefore be seen that rotation of shaft 14 serves to raise and lower the side head 16. The shaft 12 is provided with the usual bevel gears shown in Fig. 1 which mesh with similar bevel gears in the rail heads 7 and 8 and serves to raise and lower the same.

The mechanism for operating the dial feed will now be described. Keyed on the right hand end of sleeve 36 (Fig. 7) is a gear 60 which meshes with a gear 43^a and a gear 61 rotatably mounted adjacent the end of shaft 14 and having a clutch face 62 adapted to engage with clutch 40. Secured over the outer end of feed adjusting shaft 15 is an operating member 63 adjacent which is a suitable dial 64. Rotatably mounted on the sleeve 36 adjacent the left hand end thereof is a gear 65 the inner end of which is provided with a cam surface 66. Keyed on the left hand end of sleeve 36 is a clutch member 67 which is urged toward the right as seen in Fig. 7 by means of a coil spring 68. Keyed on the shaft 15 adjacent the inner end thereof is a

member 69 in which is slidably mounted a pin 70 carrying a depending cam roller 71 which is disposed in front of the flange 72 on clutch member 67. The cam roller 71 bears 5 against the rear face of the gear 65 and when the cam surface 66 is moved opposite the cam roller the clutch member 67 will be moved to the left as seen in Fig. 7 to disengage the clutch thereby disconnecting the drive between the gear 65 and the sleeve 36. By 10 turning the shaft 15 by means of operating member 63 the position of the cam roller 71 with respect to the cam surface 66 may be varied.

15 Extending through the rail 6 and meshing with the gear 65 is a reciprocating rack bar 73 to the lower end of which is connected a crank arm 74. Projecting outwardly from the table bed is a shaft 75 which is enclosed 20 within a suitable housing and is driven in opposite directions by the table 2. Keyed on the shaft 75 is a friction disk 76 which is enclosed by a friction cup 77. Arranged within the friction cup 77 and pivotally secured thereto are a pair of friction clutch bands 78 and 79 which are pivotally secured at their upper ends as at 80. The lower ends of the bands 78 and 79 project through the cup 77 and are connected by pins 81. Coil 25 springs 82 secured over pins 81 urge the friction bands into gripping engagement with the disk 76, thereby forming a driving connection between the shaft 75 and friction cup 77. Pivotally secured between the lower 30 ends of the friction bands 78 and 79 is a clutch releasing bar 83 which is adapted to strike against stops 84 and 85 provided on the end of the planer bed and thereby releasing the driving connection between the shaft 75 and the friction cup 77. The portion 76a of the 35 friction cup 77 is provided with a pair of oppositely disposed openings 86 and 87 and loosely mounted on the outer end of shaft 75 is a disk 88 having an opening 89 therein.

40 The crank arm 74 at its lower end is provided with a spring pressed plunger 90 which extends through the opening 89 and which may be inserted into either the opening 86 or 87 to form a driving connection between the portion 76a of the friction cup 77 and the 45 rack bar 73. It will thus be seen that a driving connection between the rack bar 73 and shaft 75 is provided for a 180 degree movement of the shaft 75, and that as soon as the 50 clutch release bar 83 strikes either the stop 84 or stop 85 this driving connection will be broken. It will now be clear that the movement of the rack bar 73 and gear 65 will always be the same regardless of the length of the stroke of the table 2 which drives the shaft 75. It will also be clear that by turning the 55 feed adjusting shaft 15 by means of the operating member 63 the relative position of the cam surface 66 and cam roller 71 may be adjusted to control the feed of both the rail 60 and the side head. By setting the plunger 90 in either the opening 86 or 87, the feed may be adjusted at either end of the stroke. When any one of the clutch members 40, 45, 46 or 47 is moved to the right, as 70 viewed in Fig. 6, a driving connection will be provided for the feed for one of the heads, the power being transmitted from the rack bar 73 through sleeve 36, gear 60, and gears 61, gears 43a, 42a and 44a and clutch members 40, 45, 46 or 47 to one of the shafts 11, 12, 13 or 14, the feed being regulated by setting the feed shaft 15 as hereinbefore described. By moving the clutch members to the left from the neutral position (Fig. 6) any one or all 75 of the heads may be connected with the rapid power traverse. Various changes may be made in the details of the mechanism hereinbefore described and it is to be understood that the invention is to be limited only in accordance with the scope of the appended claims.

80 Having thus described my invention, what I claim is:

1. In a planer, tool control means including a plurality of threaded tool control shafts, a secondary dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gear, a main power traverse gear journaled concentric to said sleeve and driving all said power traverse gears, a driving gear rotatably mounted on said sleeve, means for driving said driving gear and said main power traverse gear, and means for periodically and automatically connecting said sleeve with said driving gear. 90

95

2. In a planer, tool control means including a plurality of threaded tool control shafts, a secondary dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gears, a main power traverse gear journaled concentric to said sleeve and driving all said power traverse gears, a driving gear rotatably mounted on said sleeve, means for driving said driving gear and said main power traverse gear, and means for periodically and automatically connecting said sleeve with said driving gear. 100

105

3. In a planer, tool control means including a plurality of threaded tool control shafts, a secondary dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gears, a main power traverse gear journaled concentric to said sleeve and driving all said power traverse gears, a driving gear rotatably mounted on said sleeve, means for driving said driving gear and said main power traverse gear, and means for periodically and automatically connecting said sleeve with said driving gear. 110

115

4. In a planer, tool control means including a plurality of threaded tool control shafts, a secondary dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gears, a main power traverse gear journaled concentric to said sleeve and driving all said power traverse gears, a driving gear rotatably mounted on said sleeve, means for driving said driving gear and said main power traverse gear, and means for periodically and automatically connecting said sleeve with said driving gear, said last means including a clutch element splined on said sleeve adjacent said driving gear, and a rod 120 extending through said sleeve and carrying thereon means for controlling said clutch. 125

5. In a planer, tool control means including a plurality of threaded tool control shafts, a secondary dial feed gear and a power trav- 130

- erse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gears, a main power traverse gear journaled concentric to said sleeve and driving all said power traverse gears, a driving gear rotatably mounted on said sleeve, means for driving said driving gear and said main power traverse gear, means for periodically and automatically connecting said sleeve with said driving gear, the driving means for said driving gear including a rack, and means including a friction clutch for driving the same from the planer bed.
4. In a planer, tool control means including a plurality of threaded tool control shafts, a dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and meshing with said dial feed gears for driving the same, a main power traverse gear journaled concentric to said sleeve and driving all said power traverse gears, a driving gear rotatably mounted on said sleeve, means for driving said driving gear and said main power traverse gear, means for periodically and automatically connecting said sleeve with said driving gear, said means for driving said driving gear including a rack bar meshing therewith, a shaft driven from the planer bed and a friction clutch carried by said last shaft, one element thereof being fixed thereto, means for connecting the other element with said rack bar, and means whereby said clutch elements move together through a portion of a turn of said last shaft only, at the beginning of its rotation in each direction.
5. In a planer, tool control means including a plurality of threaded tool control shafts, a dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gears, a main power traverse gear journaled concentric to said sleeve and driving all said power traverse gears, a driving gear rotatably mounted on said sleeve, means for driving said driving gear and said main power traverse gear, means for periodically and automatically connecting said sleeve with said driving gear, said means for driving said driving gear including a rack bar meshing therewith, a shaft driven

from the planer bed and a friction clutch carried by said last shaft, one element thereof being fixed thereto, and means for connecting the other element with said rack bar.

6. In a planer, tool control means including a plurality of threaded tool control shafts, a dial feed gear and a power traverse gear mounted loosely on each of said shafts, a clutch splined to each shaft between said gears and capable of being connected to either but not both thereof, a dial feed sleeve to which all of said shafts are parallel, a main dial feed gear keyed on said sleeve and driving said dial feed gears, a main power traverse gear journaled concentric to said sleeve and driving all said power traverse gears, a driving gear rotatably mounted on said sleeve, means for driving said driving gear and said main power traverse gear, means for periodically and automatically connecting said sleeve with said driving gear, said last means including a clutch element splined on said sleeve adjacent said driving gear, a clutch face on the end of said dial feed driving gear adjacent said clutch element, a rod extending through said sleeve, a cam on said driving gear, a shoulder on said clutch element, and means carried by said rod and working between said shoulder and cam for disconnecting said clutch after a predetermined rotation of said sleeve.

In testimony whereof, I hereunto affix my signature.

J. JENNE. 100
